UNITED STATES PATENT OFFICE.

SAMUEL J. VAN STAVOREN, OF PHILADELPHIA, PENNSYLVANIA, ASSIGNOR OF TWO-THIRDS TO SMITH W. CLARK, OF DELANCO, NEW JERSEY, AND CHARLES F. VAN HORN, OF PHILADELPHIA, PENNSYLVANIA.

ATTACHMENT FOR BRICK-MACHINES.

SPECIFICATION forming part of Letters Patent No. 509,976, dated December 5, 1893.

Application filed December 19, 1891. Serial No. 415,594. (No model.)

To all whom it may concern:

Be it known that I, SAMUEL J. VAN STAVOREN, a citizen of the United States, residing at Philadelphia, in the county of Philadelphia and State of Pennsylvania, have invented 5 certain new and useful Improvements in Attachments for Soft-Mud-Brick-Making Machines; and I do hereby declare the following to be a full, clear, and exact description of the 10 invention, which will enable others skilled in the art to which it appertains to make and use the same.

My invention has relation generally to making soft-mud green-brick, and particularly to 15 the shaking, dumping and bearing off operations required for soft-mud brick making machines.

It is well known that in molding green 20 brick by machinery, all the work of shaking the molds as they come from the machine for loosening the green brick in the molds, of dumping the loosened brick from the molds onto pallet boards and of stacking the latter on cars or in racks, is manually done; that 25 such work is laborious and requires skillful operators to preserve the square form of the brick or to avoid making bad-brick, to prevent waste, and to keep up with the full capacity output of the machine. To admit of 30 the best possible conditions of performing the work of shaking and dumping relatively with commanding the full capacity output of the machine, the degree of stiffness of the soft mud green-brick is low, and hence when un- 35 skillfully handled they are apt to lose their square form and more time is consumed in drying them than would be the case if their degree of stiffness were high.

My invention has for one of its objects to do 40 the work of shaking and dumping the green brick from the molds mechanically whereby the output or capacity of the machine and the degree of stiffness for the green brick may be increased as desired.

Another object of my invention is to mechanically shake, dump and stack the green-bricks, and also to return the empty molds to 45 the sander, and further if desired to mechanically insert the sanded molds into the brick machine.

A still further object of my invention is to smooth the rough top or open surface of the green-brick in the molds while upon the delivery table and after they are ejected from the machine.

My invention accordingly consists mainly 55 of a soft mud brick making machine having a mold shaking device, a mold dumping device, conveying or transferring mechanism interposed between the shaker and dumper 60 devices, which mechanism preferably acts to turn the top or open side of the mold downward during its transfer from the shaker to the dumper in order that a square vertical lift may preferably be imparted to the dumper, a transferring device from the dumper to the sanding machine for returning the empty molds to the sanding machine and a device for mechanically stacking the pallets of green-brick on the trucks or cars, and further to a 70 device for mechanically inserting the sanded molds into the brick making machine, to a presser or roller device at the delivery end of the brick machine for smoothing the top side or surface of the brick in the molds after the 75 latter are projected from the machine, and to the combinations, constructions and arrangements of parts as hereinafter more particularly described in the specification and pointed out in the claims.

Reference is had to the accompanying drawings, wherein—

Figure 1 is a diagrammatic plan of part of a brick machine and a mold sanding machine with a form of shaking, dumping and stacking attachments, a device for returning the molds to the sanding machine and for inserting the sanded molds into the brick machine embodying my improvements. Fig. 2 is an elevation showing one form of stacking device. Fig. 3 is an elevation showing an advantageous construction of pallet for use with the form of stacking device shown in Fig. 2. Fig. 4 is a front elevation of a form of soft mud brick machine showing a form of shaking device for the molds; the latter being partly in section. Fig. 5 is a plan of the mold shaking supporting table detached from the machine. Fig. 6 is a section on line 1 to 1 Fig. 4. Fig. 7 is an end view of part of the 95 100

shaking device and a form of knocker arms for the ends of the molds to hit against as they are shaken. Fig. 8 is a perspective view showing more plainly the preferable form of such knocker arms and mold supporting table ends. Figs. 9 and 10 are elevations showing different forms of actuating cams for the shaker. Figs. 11 and 12 are elevations illustrating different forms of shakers and actuating devices therefor. Fig. 13 is a sectional elevation showing another form of shaker with actuating devices for imparting to it an angular reciprocating motion to loosen the heads as well as the sides of the bricks in the molds when shaken. Fig. 14 is a section on the line 2. 2. Fig. 13. Fig. 15 is a plan showing still another form of shaker device. Fig. 16 is a side elevation of the same. Fig. 17 is a diagrammatic sectional elevation of part of the front end of a soft mud brick machine, shaker device, the dumper device, transferring devices between the shaker and the dumper, a pallet-feeding device and part of the devices for conveying the empty molds from the dumper to the mold sanding machine. Fig. 18 is an elevation, partly sectional of the pallet feeding device and the mold-reversing device. Fig. 19 is a like view showing the operation of the pallet-feeder. Fig. 20 is a plan partly sectional of said pallet feeding device. Fig. 21 is a perspective of the movable bottom for the pallet-feeding device. Fig. 22 is a section on line 3 to 3 Fig. 17, partly in elevation, showing more plainly the mold-reversing device which is a part of the mold-transferring devices between the shaker and dumper. Fig. 23 is a front elevation of said mold-reverser with the pallets and molds removed therefrom. Fig. 24 is an elevation showing an end view of rollers with their actuating mechanism, preferably used for forcibly projecting the shaken molds into the mold-reverser device. Fig. 25 is a side elevation of the same. Fig. 26 is an elevation of a form of pawl and ratchet mechanism for actuating mold reverser device. Fig. 27 is a diagrammatic elevation illustrating another form of mold-reverser devices. Fig. 28 is an end elevation of the dumping device. Fig. 29 is a longitudinal section of the same showing a loose finger or tripper with reaction devices for engagement with the handles or ends of the molds as at present constructed, such finger or fingers being shown in engagement with the mold and in their lowered position previously to being raised to lift the mold from the bricks. Fig. 30 is a perspective of such finger and its sliding support detached from the dumper device. Fig. 31 is a view similar to Fig. 29 showing the bricks dumped and the mold elevated to the initial transferring devices which convey the empty molds from the dumper device to the mold sanding machine. Fig. 32 is a perspective of a part of a mold showing location of handle as at present used. Fig. 33 is a like view showing an advantageous construction of location of han-

dle for use with my dumping device; such location of handle admitting of the use of a rigid or fixed finger in the dumper device for engagement with the molds. Fig. 34 is a sectional elevation showing such an advantageous form of mold, and finger. Fig. 35 is a cross section of the same drawn to a small scale. Fig. 36 is a diagrammatic elevation of a car-truck and the stacking device partly in section. Fig. 37 is a section on the line 4 to 4 Fig. 36. Fig. 38 is a plan of the stacking device shown in Fig. 36 partly in section, Fig. 39 is a longitudinal section of a modification of the stacking device shown in Fig. 36. Fig. 40 is a section on the line 5 to 5 Fig. 39. Fig. 41 is an elevation of the lower rear end of the stacking device shown in Figs. 36, 38 and 39, and actuating mechanism. Fig. 42 is an elevation illustrating a modified construction of the frame for the stacker device. Fig. 43 is a sectional elevation showing the terminal transferring devices for conveying the empty or dumped molds from the dumper device to the mold sanding machine, a form of the latter, devices for reversing the molds as they come from the sanding machine, and for inserting them into the brick making machine. Fig. 44 is a longitudinal section through the mold sanding machine, partly in elevation. Fig. 45 is an end view of front end of brick machine shaker device and an adjustable roller device for smoothing the rough upper sides of the bricks in the molds as they are ejected from the machine. Fig. 46 is a front view of roller, cleaning and polishing brush therefor and mold. Fig. 47 is a diagrammatic view showing modified arrangement of shaker and dumper devices relatively to the brick making and mold sanding machines. Fig. 48 is a side elevation showing another form of dumping devices and Fig. 49 is a detailed view of the same.

A represents a plastic clay brick making machine of any suitable form or kind. In the drawings I have illustrated a form of the same known as the "Henry Martin machine" as it is the one now most commonly used and the construction and operation of which are well known. A' represents the delivery end of said machine, B the shaker device, C the knocker arms for the shaker device, E the dumper device, D the transferring devices between the shaker and the dumper, F the stacker device, H the mold sander device, G the transferring devices for conveying the dumped or empty molds from the dumper device to the mold sander machine, K the transfer devices for conveying the sanded molds from the sanding machine to and inserting them into the brick making machine. All of these devices may be constructed and arranged relatively to one another as desired, or the demands of service require, as their general or detailed arrangement and their construction, operation and actuating mechanism may be greatly changed for accomplishing the purposes of my invention without de-

parting from the spirit thereof, and hence I do not limit myself to the various arrangements and constructions of the forms herein shown and described.

5 The shaker device B consists mainly of a table or platform *b*, which has a to and fro motion from end to end across the front of the brick making machine or its delivery platform, to cause the ends of the mold to alternately strike the oppositely located knocker arms C, to loosen or shake the bricks in the molds preparatory to dumping them. The table *b* may be of any suitable construction. In the drawings, see more plainly Fig. 5, it is shown provided with reduced ends *b'*, having upwardly projecting edge flanges *b*². These reduced ends pass into openings or recesses *c*, in the knocker arms C, so as to admit of the ends *l* of the long sides *l'* of the molds L striking the knocker arms C, without the plate *b*, hitting said knocker arms. With this construction the impact of the blow falls upon those parts of the mold best able to resist or endure it, thereby providing for maintaining the durability of the molds, the same as in hand shaking.

The table or platform *b*, in Figs. 4, 6, 7 and 11 is shown having a rod connection *b*³, with a second plate *b*⁴, sliding in suitable lugs, and provided with interposed buffer springs *b*⁵, to compensate for shocks and concussion. In Figs. 4 and 6 the second table or platform *b*⁴ is shown provided with a roller support *b*⁶, being held or guided thereon as indicated more plainly in Figs. 6 and 7, or such support may be otherwise provided for as desired. With this construction the plates *b*⁴, *b*, and the mold L on the latter are simultaneously moved to and fro, but as the plate *b* and the mold are independent of the table *b*⁴, by reason of the sliding rod connection *b*³ with the interposed buffer springs *b*⁵, the table *b*⁴, and actuating mechanism and engagement therewith are almost wholly free of the impact or strains incident to the striking of the ends of the molds against the knocker arms.

Any suitable actuating mechanism may be employed for imparting the to and fro movement to the table *b*—preferably a form of the same is used which will give the table the required number of reciprocations for properly shaking the molds and then bring the table and mold to rest or dwell to admit of the mold being moved from the table to the devices D, which transfer it to the dumper device.

In Figs. 9 and 10 is shown a disk or wheel *b*⁷, attached to actuating shaft *b*⁸, and having an actuating and dwelling groove *b*⁹, which is in engagement with a suitably arranged movable lever *b*¹⁰, having an engagement with the table *b*⁴ as shown more plainly in Fig. 4.

In Fig. 11 the table *b*⁴ is illustrated provided with end link supports *b*¹¹, which are in engagement with the lever *b*¹⁰.

In Fig. 12 the links *b*¹¹ are shown connected

by a cross bar *b*¹², which has a direct engagement with the actuating and dwelling groove *b*⁹, and disk *b*⁷.

In Fig. 13 the table *b*, is indicated as having a wheel or roller support on the fixed end of the brick machine, and the lever *b*¹⁰ is provided with the sliding rod connection *b*³ in engagement with said table by means of vertically arranged rollers or bars *b*¹³, the buffer springs *b*⁵ being interposed as shown. By providing an angularly arranged slot *b*²⁰ lengthwise of the fixed delivery end, as shown more plainly in Fig. 14 through which the rollers *b*¹³ pass, the table *b*, and the mold thereon are simultaneously moved to and fro, lengthwise and laterally, or angularly reciprocated for correspondingly striking the knocker arms C, which has the effect of loosening the ends or heads as well as the sides of the bricks in the molds.

In Figs. 15 and 16 the table *b*, is shown provided with an extension pivoted at *b*¹⁴, said extension having suitable buffer connection with the actuating devices as desired. In this last described form the table *b*⁴ has a curvilinear reciprocating motion.

It will be noted that in all the forms of shakers B illustrated and described, the shaker carries with it the mold and the power devices move both the shaker and mold, but it is obvious that the mold and shaker may be otherwise relatively arranged and the power appliances actuated to shake the molds as desired.

The molds L, with their open tops are projected from beneath the strip or bar *a*, of the machine A, in the usual or any desired manner. As they are delivered from the machine they successively pass onto the shaking table *b*, which is then normally at rest to receive the molds, the mold previously shaken being pushed off of the table *b*, by the succeeding delivered mold. As the shaken mold passes off of the table *b*, it is conducted to a mold-reversing device D', which is a part of the devices D, for transferring the molds from the shaker device B to the dumper device E. Any suitable form of mold reversing device D' may be employed. In Fig. 17 an intermittent rotary form is shown, consisting of a shaft *d*, end frames *d'*, said shaft having any suitable actuating mechanism, a pawl and ratchet device *d*² for instance, having a sliding bar *d*³, and cam *d*⁴ engagement, on shaft *b*⁸, if desired.

The end frames *d'*, of mold reversers D', are provided with radial slots *d*⁵, wide enough to receive the molds and pallets as they are fed thereinto. The bottom sides of these slots *d*⁵, when at rest in front of the shaker device are level with the top of the table *b*, and into each of these slots as they successively arrive into their receiving position in front of the shaker device is conducted a mold coming from the shaking table. Preferably in order to facilitate the quick transit of the molds from the shaking table *b*, into the recesses *d*⁵, and to

provide for a side blow of the mold against the inner ends of said recesses d^5 , for shaking the brick lengthwise to loosen its head from the molds, suitable revolving rollers one or more as indicated at a^8 , are interposed between the shaker device B, and mold reverser D'. These rollers are suitably mounted in the delivery platform of the brick machine A for instance, and are in engagement with an actuating shaft b^8 , if desired, for imparting to said rollers a speed much higher than that of the travel of the molds from the machine. This high speed conducts the mold from the shaker table b, and into the receiving recess 15 d^5 of the reverser D', with sufficient velocity to cause the mold to travel to and strike the rear end of the receiving recess with the required impact for loosening the heads of the brick from the mold. As the mold passes into 20 the receiver recess of the reverser D', a pallet a^4 of the usual or other suitable construction is placed upon the top of the mold. The pallet may be put on the top of the mold before it enters the recess, which if desired may be 25 manually done. The position of the pallet on the mold in this case is with the top or face contiguous to the top of the mold, the feet of the pallet projecting upwardly. The distance apart of the frames d^1 of the reverser D' is such, that they are adjacent to and form guides for the inner sides of the feet 30 of the pallet so that as the mold and pallet pass into a recess d^5 the pallet is properly adjusted lengthwise relatively to the mold. To insure quick feeding of pallets into the recesses d^5 , I prefer to do the same mechanically. To this end a suitably located pallet receiver or supply receptacle a^{24} is provided. This is shown hinged or swung upon suitable 35 supports above the shaker device and mold reverser D', and it has an oscillating motion to and from the receiving recess d^5 of the reverser D'. In the form of receptacle a^{24} shown it is provided with an open bottom 40 a^6 , hinged at its rear end to the receptacle as indicated at a^6 . See more plainly Figs. 18 to 21 inclusive. The bottom a^5 , has reaction devices a^7 for holding it normally closed, a rear inner lower edge a^8 , and front 45 inner and inwardly projecting short pins or studs a^9 . This ledge and these studs support the pallets placed in receptacle a^{24} , with their feet upwardly, as indicated more plainly in Fig. 17. The front side a^{10} , at its lower end 50 is cut away or opened equal to the depth of the pallet as more plainly indicated at a^{11} , Fig. 20, which opening is provided for the escape of the pallet as it is fed onto the mold in the receiving recess of the reverser D'. 55 The receptacle a^{24} is so hung that as it approaches a recess d^5 , the lower pallet in the receptacle is in line with the top of the mold as indicated by dotted lines α Fig. 18, so that when the outer edge of said pallet meets the 60 top of the mold, and the upper edge of the receiving recess d^5 , the hinged bottom a^5 yields to permit the forward oscillation of the

receptacle a^{24} , to carry the pallet in a straight line into the recess to the full limit thereof and properly position the pallet on the mold 70 as indicated in Fig. 19. As the receptacle a^{24} is withdrawn, the bottom a^5 closes to retain the succeeding pallets therein. Any suitable crank and link connection a^{12} , with a like crank on an actuating shaft b^8 for instance 75 may be employed for oscillating the receptacle a^{24} . At each movement of the mold reverser D' a mold and pallet are inserted into one of the recesses d^5 , on one side of said reverser, and 80 a like mold and pallet moved out of a delivery recess on the opposite side. In the interval between the insertion of the mold and pallet into the reverser and its delivery therefrom, owing to the rotation of the reverser, the 85 mold and pallet are reversed, that is to say the mold is on top and the pallet below, which is the proper position for raising the mold from the pallets to dump the brick. When the reverser brings a mold and pallet into delivery position, the feet of the pallet come onto parallel ways or guides d^6 Fig. 22 and the body of the pallet is adjacent to an endless apron or traveler d^7 located between its feet, or the ways d^6 . This traveler or apron d^7 is 90 provided with outside transverse cross strips or fingers d^8 , preferably of a form in cross section that they will meet and abut against both the pallet and the mold as they are brought into delivery position by the reverser D', for transference to the dumping device E. As 95 the pallet feet rest on the ways d^6 , the weight of the pallets and molds are removed from the traveler d^7 . The latter is actuated by a belt or other connection from the actuating 100 shaft b^8 or otherwise as desired to give it an intermittent motion corresponding to that of the reverser D'. A reversed mold and pallet 105 conveyed to the dumper device are brought into alignment with mold elevating devices 110 e , having an up and down motion on a suitable frame e' and actuated by suitable cams e^2 , on shaft e^4 , through the medium of bars e^3 , said shaft e^4 having if desired a belt connection e^5 with the actuating shaft b^8 or otherwise as desired. 115

When the form of mold shown in Fig. 32 is used as it is at present customary, that is to say, with the handles l^2 at the top of the molds, the elevating devices e are provided 120 with pivoted or movable catches or fingers e^6 , having suitable reaction devices for maintaining them in normal position to engage the handles of the mold and lift it from the brick when the devices e^6 are elevated. See 125 more plainly Figs. 29 and 31. If the mold be made as illustrated in Fig. 33, that is with the handles at the ends at the bottom of the mold, rigid fingers e^6 are employed for the elevating devices e as shown more plainly in 130 Figs. 34 and 35. As each succeeding mold or pallet is delivered to the dumping device, its elevating mechanism e engages the ends of the mold, and elevates it from the pallet,

leaving the brick thereon, which pallet and brick are by a succeeding movement of the traveler or apron d^7 removed from the dumper device, from which apron or traveler the pallet and brick may be manually taken and placed on cars, trucks or otherwise disposed of as desired. The mold when elevated from the pallet may be manually removed from the lifting devices e and returned to the sanding machine. I prefer however to mechanically return the empty molds to the sander and to this end, the frame e' of the dumping device in line with the path of upward movement of the molds is provided with hinged or pivoted 15 guide ways e^7 , having lower inside cammed edges e^8 against which the top of the mold strikes to spread apart these guide ways and admit of their returning to their normal position below the mold after being elevated. 20 These ways are preferably inclined and provided with roller bearings so that when the mold is free to do so, it will by gravity travel along said guides to other or fixed guides g , or the guides g may be a traveling apron as 25 indicated at g' Fig. 31. The guides g , see more plainly Fig. 1 are located transversely across a traveling apron g^2 , which leads to the sanding machine H , so that an empty mold traveling along the guides g is deposited on 30 the apron g^2 and by it carried to the sander H ; a suitable buffer g^3 at the ends of guides g limits the travel of the mold on said guides so that it will fall from the guides onto the apron g^2 in proper position to be transferred to the 35 sander. Any suitable form of sander may be used.

In the drawings I have illustrated a sander, composed of the shaft h , upon which are end wheels h^2 , having outer belt or fixed sheathing h^3 . The shaft h is preferably hollow as 40 shown more plainly in Figs. 43 and 44, and one end is provided with a hopper h^4 swiveled to the shaft at h^5 and into which the sand is manually shoveled or conducted from the 45 grinder or place of supply. The sand from the hopper passes into the hollow shaft h , and through openings h^6 therein falls into the sander. Any suitable spiral or analogous conveyers h^7 may be located in the bore of 50 shaft h to assist the passage of the sand through the same. The wheels h^2 are provided with radial lugs h^8 which engage the ends of successive molds as shown more plainly in Fig. 43, and carry them through the sander 55 up to and on the plate h^9 from whence they are transferred by roller or rollers h^{10} having belt connection h^{11} , see Fig. 1—with shaft b^8 or as desired. The molds so delivered from the sander are bottom upward and must be reversed when inserted into the brick machine, 60 and to this end the rollers h^{10} conduct the successive molds to a reversing plate k , having a front upwardly projecting ledge k' . This plate is so pivoted at k^2 , that its rear end k^3 overbalances its front end to return it to its normal or horizontal position, to receive the mold. The weight of the latter on the plate causes

it to tilt at its forward end to turn the mold over so as to bring its open side up and deposit it on a traveling apron or conveyer k^4 70 leading to the entrance opening k^5 for the mold in the machine A . Suitable guides k^6 k^7 parallel and adjacent to the edges of the traveling apron k^4 , are provided for positioning the reversed mold as it drops onto apron k^4 and also during its travel thereon and insertion through the opening k^5 into the machine A .

The roller or rollers h^{10} are preferably high speeded so as to cause the molds to be quickly 80 conducted to the tilting plate k , in order that it may have sufficient time to perform its function and return to normal position to receive the successive molds, fed onto the plate h^9 by the slower travel of the wheels h^8 . 85

It will be noted from the foregoing that the molds with the brick as they are successively delivered from the brick making machine are mechanically shaken and dumped, and the empty molds are correspondingly returned to 90 the sanding machine, sanded and properly positioned for mechanical insertion into the brick making machine, thereby dispensing with the services of shaker, dumper and a sander man for those purposes. The output 95 of the machine is therefore not limited and may be increased to the full capacity of the brick making machine and the molds are uniformly shaken and dumped with precision, preserving the form and shape of the 100 brick and insuring the production of regular and better stock, all of which is accomplished at very material reduction in cost.

I have stated that the dumped bricks carried forward by the traveler e^6 may be manually taken therefrom and stacked on cars. I prefer that the same should be mechanically done as quicker and better stacking can thereby be effected without damage to the stock and the high priced labor usually employed therefor is dispensed with.

The essential requirement of the mechanical stacker is that it must be so constructed that it can be raised with the growth or piling of the stack, and can be contracted or extended 115 as the variant locations of the different pallets in the different stacks necessitate. The stacker F is therefore pivoted or hinged so that it can be gradually raised from the bottom to the top of a stack and then quickly 120 lowered to begin the succeeding stack. It also is made in sections so that its length can be expanded as it is raised in building the stack and contracted as required in directing the central and the outer stack next to the 125 stacker.

In Figs. 1 and 2 a form of stacker is shown located in front of the traveler or apron e^6 and connected thereto by a frame f provided with aprons or traveling chains f' to continue the 130 movement of the pallets with the bricks thereon to the stacker, and also to provide for freedom of pivoting the stacker so that it can be raised as the growth of the stacks require.

- The stacker F consists essentially of a supporting frame or side bars f^2 pivoted or hinged upon the front shaft f^3 of frame f . These side bars have segmental or other gears f^4 fixed thereto concentric with the axles of the shaft f^3 and are in gear with mutilated pinions f^5 on a shaft f^6 , which mutilated pinions act at intervals to raise or step up the stacker F after each succeeding pallet has been deposited in the stack, suitable pawl or other retaining devices f^7 being provided for engagement with the gears f^4 for retaining the stacker in its raised position. These pawls are released manually or otherwise when it is desired to lower the stacker after the completion of a stack. The form shown in Figs. 1 and 2 is provided with one movable section f^8 having traveling bands or chains f^9 , racks f^{10} in engagement with a gear wheel o mounted upon a shaft o' supported in the frame f^2 and having an operating winch or handle f^{12} whereby the front end f^{13} of section f^8 is projected away from or brought to the frame f^2 to extend or contract the stacker as desired. Upon the shaft f^{14} at the front end of the section f^8 are loosely mounted ways or guides f^{15} which are so hung that they maintain themselves or are held in a horizontal position relatively to the variant positions of the stacker. Said shaft is provided with wipers f^{16} which rotate with the shaft. The pallets with brick thereon conveyed to the stacker are successively caused to travel to the front end of the stacker, and out upon the ways or guides f^{15} by means of the bands or chains f^9 , the wipers f^{16} moving the pallets off of the ways f^{15} to effect their stacking. When the ways f^{15} are constructed as shown in Figs. 1 and 2 the ways f^{15} are withdrawn from beneath the pallet after it is stacked by manual manipulation of the stacker. If the pallets are constructed with their feet removed slightly from their ends as shown in Fig. 3 and the ways or guides f^{15} be hinged or pivoted to the section f^8 then the guides may in any suitable manner, either by gravity or mechanically be moved laterally out from beneath the pallets as indicated by dotted lines in Fig. 3 without necessitating any manual operation of the stacker f^4 releasing said ways or guides from the pallets preparatory to stepping the stacker.
- In Figs. 36 to 39 inclusive a form of stacker is shown having two or more extensible sections and which more plainly show how the bands or chains f^9 are elongated or contracted correspondingly with like movements of the sections of the stacker, said bands passing around a floating weighted sprocket or other cylinder f^{17} . In these forms the outer section f^8 is provided with a traveling carrier T, which engages pallets and conveys them to the stack. The traveling carrier T has its movements on tracks t , and is provided with hinged catches t' , which engage the pallets as shown more plainly in Fig. 37. Suitable trippers t^2 are provided for releasing the

catches t' from the pallets in the act of depositing them upon the stack. The carrier T is moved to and fro by traveling band t^3 actuated by the shaft f^{14} of section f^8 through intermediate mechanism t^4 . The traveling carrier T may have an up and down motion also, in addition to its to and fro movement as illustrated more plainly in Figs. 36 and 37. When it has a to and fro movement only, it is connected to the traveling band t^3 as shown in Figs. 39 and 40. The ways f^{15} in these forms are of short length and do not extend to the line of the stacks. Said ways, carrier T, its tracks, driving belt t^3 and power transmitting devices t^4 are all mounted in a suitable frame t^5 pivoted or hinged on the shaft f^{14} of section f^8 so as to maintain its horizontal position relatively to that of the stacker, such maintenance being provided for by suitable gravity acting devices or by levers, links mechanical or other suitable appliances. If desired the sections of the stacker may be tubular as illustrated in Fig. 42. In these forms of stackers the gear wheel f^5 for stepping stacker is not mutilated and such stepping movements are controlled by friction or other clutching mechanism m , the gear wheels f^5 being loose on their shaft. See more plainly Fig. 41.

In Fig. 45 is shown a roller N preferably speeded, located between the shaker and the stripper bar of the machine for smoothing the rough upper sides of the brick in the mold. Said roller is mounted in a hinged frame n and has pressure devices n' for regulating the degree of its rolling pressure upon the brick in the mold. Said roller is provided with a scraper n^2 having pressure screw n^3 and with a pressure brush or pad n^4 for keeping its surface clean and bright, thereby preventing the brick adhering to the roller, and admitting of it effectually accomplishing its functions. The roller N, it will be noted, is so mounted in its supporting frame n , that the roller does not come into action until after the mold is ejected from the machine or from beneath the scraping knife or device. The knife or scraper and the roller N are acting upon different molds at the same time, or in other words, the roller N is smoothing the top surfaces of the brick in a mold in advance of the one being ejected from the machine and acted upon by the scraper. The actions of scraping and rolling the green brick in the molds, are, therefore, successive actions and not simultaneous ones as heretofore has been the case, and all crowding or banking of clay against the outer edge of the scraper is avoided.

In Fig. 27 a modified form of carrier reverser D' is shown which consists of a tilting plate p weighted at its rear end to return it normally to a horizontal position, and of a second plate p' tilting on a sliding carriage p^2 . The rear end of plate p' is weighted to bring it normally to an angular position. A mold fed to the plate p overbalances its front end and tilts it in the direction of arrow 1.

Fig. 27. As such tilting occurs the inclined plate p' is approaching the plate p , and is in position to receive the tilted mold upon the pallet previously placed upon the plate p .
 5 As soon as the tilted mold impinges against the pallet on the plate p' the weight of the mold tilts plate p' to a horizontal position, thereby reversing the mold, and a carriage p^2 is then actuated to convey the pallet and
 10 mold to the dumper device.

In Fig. 47 is shown a modification of location of the dumping device in which the latter is located in front of the sander, instead of in front of the brick machine, in which
 15 case a traveling band R conveys the molds, after they have descended by gravity from the partial platform r , to the mold reverser D' . In this position the ways or guides g will lead directly into the sander and the traveling belt g^2 be dispensed with. So too, traveling aprons may be substituted for said guides, the use of either depending upon the relative height of the sander, mold reverser, and dumper device.

25 In Fig. 48 is shown a modified form of dumper device consisting of a continuously traveling apron chain or belt, V , to which are attached the elevating devices e , which run on tracks as shown. The traveler V has the
 30 same speed as the traveler d' , which in this case also runs continuously. The front end of traveler V is higher than its rear end, and the tracks for the elevating devices are correspondingly arranged, so that as the latter
 35 are moved by the traveler when in engagement with the mold, up the inclined tracks and in so moving the elevating devices and mold are raised from the brick.

Fig. 49 shows the detailed construction of
 40 these last described elevating devices, and trippers for releasing them from the molds when they are conveyed to the guides or aprons g , g^2 , for transfer to the sander.

While I have described my invention as
 45 being particularly applicable to soft-mud brick making machines I do not confine myself thereto, as so much of the same as is necessary may be used in connection with stiff mud brick machines wherein the brick is placed upon pallets and stacked upon cars.

It will be noted that in the operation as a whole, the mold L is first delivered to the shaker B , which shakes the mold. The shaken mold is then passed to the transferring device
 55 D' , and supplied with a pallet and turned top side downward with the pallet in position upon the belt or apron d' . The latter moves the mold and pallet to the dumper E . The mold is raised from the bricks and passes by
 60 way of the transferring devices G to the sander H , and from the latter by way of the transfer devices K to the brick machine. Meanwhile the pallet of dumped bricks passes by way of the belt or apron d' to the stacker
 65 F and by it is stacked upon the car.

What I claim is—

1. In combination with the mold delivery

end of a brick making machine a mold shaking device, a dumping device, means interposed between said devices for transferring
 70 the mold from the shaking to the dumping device substantially as set forth.

2. In combination with the mold delivery end of a brick machine having fixed knockers at each side thereof, a mold shaking device, a power shaft, and actuating mechanism interposed between said shaft and mold shaking device, for imparting to the ends of the mold an impact blow against said knockers, substantially as set forth.

3. In combination with the mold delivery end of a brick making machine, a mold shaking device and actuating mechanism for simultaneously shaking the mold lengthwise and crosswise, substantially as set forth.

4. In combination with the mold delivery end of the brick making machine, a shaking device composed of a plate adapted to receive and carry the molds, actuating mechanism for reciprocating or shaking said device in an angular direction relatively to its length or width substantially as set forth.

5. In combination with the mold delivery end of a brick machine having fixed knockers at each side thereof, a mold shaking device, a power shaft, actuating mechanism interposed between said shaft and mold shaking device for imparting to the ends of the mold an impact blow against said knockers and said actuating mechanism, having means for regulating the impact of the shaking blow substantially as set forth.

6. In combination with the mold delivery end of a brick-making machine, a power shaft, a shaking table b^4 , actuating mechanism interposed between said shaft and table b^4 , a second table b supported upon the table b^4 and having cushions or springs b^5 , substantially as set forth.

7. In combination with the delivery end of a brick making machine a shaking table, actuating mechanism therefor, and a transfer or conveyer plate which automatically turns the mold upside down, substantially as set forth.

8. In combination with the delivery end of a brick making machine, a shaking table, actuating mechanism therefor, a mold reverser for automatically receiving the molds from the shaker and for correspondingly turning them top side downward and actuating mechanism for the mold reverser for effecting such automatic movement of the reverser, substantially as set forth.

9. In combination with the delivery end of a brick making machine, of a shaking device for the molds, actuating mechanism for said shaking device, a rotating receptacle for receiving the shaken molds from the shaking device and for turning the molds top side downward, substantially as set forth.

10. In combination with the delivery end of a brick making machine, a shaking table, actuating mechanism therefor, a turning or movable table for turning the molds top side down-

- ward, a movable receiver for receiving said turned molds, a dumping device for withdrawing the molds from the green-bricks therein substantially as set forth.
- 5 11. In combination with the delivery end of a brick making machine, a shaking table, actuating mechanism therefor, a turning or movable table for turning the molds top side downward, a movable receiver for said turned 10 molds, a dumping device for withdrawing the molds from the green-brick therein, and a conveyer device for returning the empty molds to the source of sanding them previous to insertion in the brick machine substantially as set forth.
- 15 12. In combination with a dumping device for withdrawing plastic green-brick from molds and depositing the brick on pallets, a conveyer device, a stacking device and actuating mechanism for said stacking device substantially as set forth.
- 20 13. In combination with a dumping device for withdrawing plastic green-brick from molds and depositing them on pallets, of a stacking device and actuating mechanism for the latter substantially as set forth.
- 25 14. In combination with the delivery end of a brick making machine, of a shaking device, actuating mechanism therefor, a rotating receiver having a number of receptacles for successive molds and actuating mechanism for said receiver substantially as set forth.
- 30 15. In combination with a brick mold shaking-device and its actuating mechanism, a receiver for the shaken molds, actuating devices for moving the receiver to turn the molds top side downward, a pallet feeding device for feeding the pallets to the receiver, and actuating devices for the pallet feeding device, substantially as set forth.
- 35 16. In combination with a brick mold shaking device, a mold receiving and turning device, a pallet feeding device and actuating mechanism for said shaker, receiving and turning and pallet feeding devices, substantially as set forth.
- 40 17. In combination with the mold delivery end of a brick machine, of a presser roller arranged relatively to the scraping device or the delivery end of the machine that a mold is first scraped as it is ejected from the machine, and successively and separately rolled after being ejected from the machine, and pressure actuating devices for said roller, substantially as set forth.
- 45 18. The combination with the delivery end of a brick-machine, a shaking table, actuating mechanism therefor, and devices interposed between the table and its actuating devices for imparting to the table an impact blow substantially as set forth.
- 50 19. The combination with the delivery end of a brick making machine, a shaking table actuating devices therefor, and cushioning devices interposed between said shaker and its actuating devices, substantially as set forth.
- 55 20. The combination of a brick mold shaking device, a mold reverser and speeded rotating rollers between the shakers and reverser for moving the shaken mold off of the shaker faster than the successive mold is fed or moved thereon, substantially as set forth.
- 60 21. A shaking device for brick molds comprising a mold supporting plate, a secondary plate supporting and moving with the mold plate and independent of the shocks or strains incident to the shaking of the mold, substantially as set forth.
- 65 22. The rotating mold reverser D' having radial recesses or slots with outer open ends and actuating mechanism for said reverser, substantially as set forth.
- 70 23. The combination with brick mold shaking devices, a mold reversing device, a dumper device, transferring appliances between the reverser and shaker devices, and actuating mechanism, substantially as set forth.
- 75 24. In combination with a mold dumping device and its actuating mechanism, appliances arranged substantially as set forth for conveying away from the dumper device the empty molds, substantially as set forth.
- 80 25. In combination with a brick making machine, a delivery apparatus for pallets of bricks, and a stacker device for stacking the pallets on a car or conveyer, substantially as set forth.
- 85 26. In combination with the delivery end of a brick making machine, of a shaker device, a mold reverser device, a dumper device, transferring mechanism between the reverser and dumper and from the latter, a mold sanding machine, transfer devices interposed between the dumper and the sander, a stacking device at the pallet delivery end of the dumper, and devices between the sander and the mold feed opening in the brick machine, for positioning the sanded molds and inserting them through said feed opening into the brick machine, substantially as set forth.
- 90 27. In combination with a mold sanding machine, a roller device at the exit end of the sander, and appliances for positioning the sanded molds and transferring them into the brick machine, substantially as set forth.
- 95 28. A brick making mold having its handles at the bottom of its ends, substantially as set forth.
- 100 29. A brick pallet having its feet removed from its ends, substantially as and for the purpose set forth.
- 105 30. In testimony whereof I have hereunto set my hand, at the city of Washington, in the District of Columbia, this 16th day of December, A. D. 1891, in the presence of two witnesses.
- 110 31. SAMUEL J. VAN STAVOREN.
- 115 32. Witnesses:
- 120 33. FRANKLIN MOORE,
CHAS. F. VAN HORN.
